UNITED STATES PATENT OFFICE

JEAN DELATTRE SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS FOR TREATING HYDROCARBONS

Application filed February 25, 1927. Serial No. 170,779.

The invention relates more particularly to the conversion of hydrocarbon oils under heat and pressure in the presence of an adsorbent agent, for the purpose of improving the qualities of the lighter hydrocarbons produced, particularly as to their sulphur content.

Another purpose of the invention is to reduce the operating cost of the so-called "cracking plants" wherein conversion of hydrocarbon oils takes place, by reducing tendency to corrosion of those parts of the apparatus which come in contact with hydrocarbon material containing objectionable sulphur compounds. One of the objects of the invention is to decrease the treating cost of the light products made, by decreasing the proportion of objectionable compounds contained therein, such as gum-forming, sulphur-containing constituents, thus rendering treatment by the usual methods now employed easier and cheaper.

Another object of the invention is to decrease the formation of pitch-like and coke-like compounds during the conversion of the hydrocarbon oil.

Briefly, the process comprises mixing with the hydrocarbon oils to be treated, a proportion of adsorbing material, such as fuller's earth, or the like, and subjecting the mixture to treatment under heat and pressure to effect conversion into lighter hydrocarbon oils.

It is readily seen that there are unlimited ways of carrying out the objects of this invention, and I do not wish to limit myself to any one particular method or apparatus. The features of the invention reside in mixing the proper proportion of the treating agent, such as fuller's earth or the like, with the hydrocarbon oil to be treated and passing the mixture through a heating zone, such as a continuous pipe coil or a still of the so-called "tube and header" type, or any other type. The mixture of hydrocarbon oil and adsorbing agent, which is raised during travel through the heating zone to the conversion temperature, may be then passed through reacting, separating and dephlegmating zones, where the heated mixture will separate into heavier and lighter fractions of unconverted

or insufficiently converted oil and into light vapors, which latter, by condensation, form the lighter final products of the operation. The coke-like and pitch-like material formed during the operation separate from the other materials in the reacting or separating zone, or both, and these zones are preferably unheated.

The lighter fractions of the insufficiently converted oil may, if desired, be returned to the heating zone for further treatment, by being added to the mixture of charging stock and adsorbing agent passing to the heating zone. The heavier liquid products of the operation are preferably evacuated from the process, but, according to their characteristics, it may be desirable to subject them totally or partially to a further treatment in the same zone as a part of the same operation.

An apparatus to carry out this invention can be conceived without difficulty by those skilled in the art, and any apparatus by which the objects of the invention can be carried out is well within the scope of the invention as long as the oil is subjected to the heat treatment and to the reaction while in the presence of an adsorbing agent, such as fuller's earth, and the like.

The adsorbing agent is generally drawn off from the apparatus with the coke-like and pitch-like heavier hydrocarbons, as well as with the heavier liquid hydrocarbons formed. The heavier liquid hydrocarbons formed in the process and which are generally suitable for use as fuel, can be separated from the spent adsorbing agent mixed therewith by distillation, or preferably, when the zone in which these liquid hydrocarbons form, is maintained under superatmospheric pressure, these liquid hydrocarbons mixed with the spent fuller's earth can be subjected to a so-called "flashing", which comprises passing them under reduced or released pressure into a separate zone where the volatile fractions separate from the non-volatile portions, and where the spent adsorbent will remain with the latter as a residue.

I will illustrate hereinafter a particular method and apparatus in which this inven-

100

tion can be carried out without limiting the invention to the application of the particular design illustrated. The single figure in the drawing is a diagrammatic and schematic view of an apparatus for carrying out the invention.

Referring more in detail to the drawing: The hydrocarbon oil to be treated can be pumped from any suitable source (not shown) through line 1, pump 2, lines 3 and 4, controlled by valve 5 to the main feed line 6, from which the oil is directed through heating tube 7 positioned in furnace 8, which can be of any suitable design and heated in any suitable manner. The oil heated in the heating tube 7, passes through transfer line 9, controlled by valve 10, into a reaction chamber 11. The conditions of operation maintained on the system can be such that the reaction in reaction chamber 11 occurs with or without substantial vaporization of the lighter constituents. Gases and vapors, if the latter are allowed to form, may pass out of the reacting zone 11, through line 12, controlled by valve 13, into a dephlegmating zone 14. The liquid products from the reacting zone 11 may be drawn off from the bottom thereof, through line 15, controlled by valve 16, and passed to a separating zone 17, where in the vapors are permitted to separate from the heavier oil, and where the separation and precipitation of the pitch-like and coke-like constituents takes place. Heavier liquid products accumulating in separating chamber 17 are evacuated therefrom through lines 18, controlled by valves 19. These heavier fractions carry out of the system a large proportion of the coke-like and pitch-like particles formed, and those which are left to accumulate are drawn off at the end of the operation through suitable manholes, such as are shown at 20.

The vapors separating in the separating zone 17 are drawn off through line 21, controlled by valve 22, and pass into the dephlegmating zone 14, where they are subjected to fractionation in any suitable manner. A cooling material can be introduced into dephlegmating zone 14, through line 23, controlled by valve 24, to assist in fractionating the vapors. The insufficiently cracked vapors which remain uncondensed in dephlegmating zone 14, pass out through line 25, controlled by valve 26, and after condensation in condenser 27 are collected in receiving zone 28, which may be provided with suitable liquid and gas draw offs, shown at 29 and 30, and controlled by valves 31 and 32.

The fractions of vapors which have been fractionated and condensed in dephlegmating zone 14 are withdrawn from the latter through line 33, controlled by valve 34, and they can be evacuated to storage through line 35, controlled by valve 36, or by diversion through line 37 controlled by valve 38, all or a

part of the condensate can be subjected to further treatment in the heating tube 7 by means of a pump 39 and line 41, controlled by valves 40 where the condensate may combine with the charging stock directed to the heating tube 7 through line 6.

By means of the various pumps and valves shown, it is readily understood that the pressure can be controlled on the various parts of the apparatus shown in a number of ways. For instance, the heating coil 7 and reactions zone 11 can be maintained under equalized superatmospheric pressure, and the latter can be reduced, by means of valves 16 and 13, to any degree above, and down to atmospheric pressure, or to such pressure as is necessary to carry the material through the balance of the system and overcome frictional resistance. If it is desired to take care of this frictional pressure in a way to reduce the pressure on the separating zone and dephlegmating zone down to, or below, atmospheric pressure, suction or vacuum pumps can be connected to the various product draw off lines from the system.

In the method illustrated, the heated hydrocarbon oil leaving the heating coils passes through separate reacting and separating zones, but it is well within the scope of the invention to combine these two zones and to allow, in this combined reacting and separating zone, all the vapors to separate from the residual products.

As a feature of the invention, an adsorbing agent, such as comminuted fuller's earth, or the like, is combined with the oil before it enters the heating coil 7, and this can be effected, for instance, in the following manner:

A portion of the oil fed through pump 2 and lines 4 and 6, to the heating coil 7, can be diverted by manipulating valves 5 and 42, into line 43, which connects with a mixing tank 44. This mixing tank can be provided with any suitable mixing or agitating means (not shown). At the same time, the adsorbing agent which may be contained in a storage or feed tank 45, provided with feed hopper 46, controlled by closure cap or valve 47, is fed into mixing tank 44, where it is thoroughly mixed by means of agitating devices with the oil passing through said tank. The mixture of adsorbent and raw oil is withdrawn from the mixing tank 44, through line 48, and by means of a booster pump 49 directed through line 50, controlled by valve 51, into the main feed line 6, and thence into the heating tubes 7. In this manner the adsorbent, mixed with a portion of the oil to be treated, mixes in line 6 with the remaining portion of the oil, and the whole mixture is subjected to treatment as heretofore described.

If desired, all the raw oil to be charged to the heating tubes can be passed through the

mixing tank 44 and therein mixed with the adsorbent, but it has been observed that the passage of a small portion of the oil through the mixing tank is sufficient to form a paste-like mixture with the adsorbent, and this paste mixes with the balance of the raw oil to be treated in as satisfactory a manner as if all the oil was mixed with the adsorbent, while it requires a smaller apparatus to do 10 the mixing.

The adsorbent passing with the oil through the heating tubes and reacting zone will remain suspended in the heavier liquid products or solid and semi-solid products which 15 separate from the vapors in the reacting and separating zones.

The mixture of the adsorbing agent and oil in mixing tank 44 is effected in such proportions as will give the final mixture entering the heating tube 7, the desired content 20 of adsorbing agent, after all the oil to be treated has mixed therewith.

The proportion of adsorbing agent to be used varies with the characteristics of the 25 oil to be treated and products to be obtained, and it may vary from, say 5 pounds to 50 pounds, more or less, per barrel of raw oil treated. This proportion may also vary if an adsorbing agent other than fuller's earth 30 is used.

The pressure and temperature must also be regulated according to the material treated and products desired; for instance, the temperature leaving the heating coil 7 may be, 35 say, from 800 to 900° F., more or less, and the pressure on the cracking zone from 300 to 600 pounds, more or less, when it is desired to produce gasoline-like distillates in the receiver 28. However, these temperatures and pressures are only given as an illustration of a particular use of the process, 40 and they may widely vary without modifying the features of the invention.

I claim as my invention:

45 1. Process of conversion of hydrocarbons under heat and pressure in the presence of an adsorbent agent, for the purpose of improving the qualities of the lighter hydrocarbons produced, particularly as to their 50 sulphur content, consisting in mixing the adsorbent agent with the charging oil for the process, subjecting the mixture to cracking conditions of temperature and pressure, separating the vapors from the residual oil 55 in which the spent adsorbent is entrained, and discharging the residual oil and spent adsorbent under a reduced pressure to permit flashing of vapors therefrom, and subjecting the first mentioned vapors and the vapors resulting from flashing to common dephlegmation.

2. Process of conversion of hydrocarbons under heat and pressure in the presence of an adsorbent agent, for the purpose of improving the qualities of the lighter hydro-

carbons produced, particularly as to their sulphur content, consisting in mixing the adsorbent agent with the charging oil for the process, subjecting the mixture to cracking conditions of temperature and pressure, 70 separating the vapors from the residual oil in which the spent adsorbent is entrained, and discharging the residual oil and spent adsorbent under a reduced pressure to permit flashing of vapors therefrom, subjecting 75 the first mentioned vapors and the vapors resulting from flashing to common dephlegmation and mixing the reflux condensate from the common dephlegmation with charging oil for the process after mixture with the 80 adsorbent material.
